Atty's.

UNITED STATES PATENT OFFICE.

DOUGLAS TURNER, OF ST. LOUIS, MISSOURI, ASSIGNOR, BY MESNE ASSIGNMENTS,
TO THE MEASUREGRAPH COMPANY, OF ST. LOUIS, MISSOURI, A CORPORATION OF
DELAWARE.

KNIFE FOR FABRIC-MEASURING MACHINES.

Application filed July 14, 1919. Serial No. 310,777.

To all whom it may concern:

Be it known that I, DOUGLAS TURNER, a citizen of United States, residing at St. Louis, in the State of Missouri, have invented certain new and useful Improvements in Knives for Fabric-Measuring Machines, of which the following is a specification.

My invention relates to improvements in knives or cutting blades, more particularly those adapted for use in machines for measuring and cutting textile fabric, such as cloth, ribbon, and the like.

The object of the invention is to provide an improved cutting means which may be readily operated, which eliminates any tendency of the knife blade to stick, and which insures a clean cut.

The accompanying drawings illustrate one embodiment of my invention, the knife constituting part of a cloth measuring machine. The invention is not limited to this embodiment, however.

Figure 1 is a side elevation of said machine, a portion of the casing being removed to disclose the interior construction, and

Fig. 2 is a section on the line 2—2 of Figure 1.

In cloth measuring machines the operator places one end of the cloth between a pair of friction rollers which are rotated as the cloth is pulled between said rollers. Suitable length indicating and price indicating charts are preferably connected mechanically to one of said rollers, whereby the rotation thereof gives the operator a visible indication of the length of material passing between said rollers, and also the price thereof at various standard prices per yard.

At the conclusion of the measurement, the operator presses a notching button thereby making a small cut or slit in the edge of the cloth, the friction rollers being simultaneously separated, thereby permitting the operator to remove the cloth from between said rollers and continue the cut with a pair of shears, completely severing the goods at the exact point representing the required measurement of length.

In the machine as made heretofore, the fabric has been cut or sheared by a pair of blades, one of which, the lower one, for example, is fixed, and the other of which

is caused to descend, cutting the fabric by the well-known shearing operation. Under certain circumstances, however, there has been a tendency for the knife blades to rub and become worn at the point where the upper and lower shear blades slide over each other, and further difficulty has sometimes been encountered by the sticking of the shear blades. The knife blade of the present invention obviates these difficulties, a construction being provided wherein, with the cloth in a horizontal plane, the knife blade is substantially vertical and moves across the fabric, the cut being made by a single blade as distinguished from a shearing operation requiring two blades. In the device illustrated, this result is accomplished by providing a blade, the cutting edge of which is disposed along a substantially spiral line, —preferably a logarithmic spiral, rotation of the blade causing the curved portion of the cutting edge to move radially outward from the axis of rotation.

The mechanism, thus briefly described, is supported primarily by the vertical plate 1, the latter being mounted on the base plate 2. The price and length indicating charts and other parts of the mechanism are located in an inner receptacle having a wall 3 arranged at right angles to the plate 1. A knife operating lever 4 is mounted on the pivoted stud 5, being preferably riveted thereto. This lever is mounted to swing in a vertical plane. The stud has a bearing in a casting 6 attached to the wall 3 preferably by rivets 7. Said stud is secured in place by a retaining washer 8 and nut 9.

The lower end of the lever 4 is provided with an arc shaped extension or segment 10 having teeth cut thereon which mesh with a spur gear 11, the latter being mounted on a stud 12 which in turn is supported by the vertical plate 1. The operator oscillates said lever by depressing a notching button 13 at the upper end thereof, thereby rotating the gear which is in mesh with the arc shaped extension at the lower end of said lever. Said lever is held in normal position against a suitable stop 14 by a spring 15 secured thereto at one end and at the other end to the vertical plate 1.

I provide a rotary knife which is rotated

from the lever 4 with an increased angular movement with respect to the angular movement of the lever.

The knife 16 is mounted to turn with the 5 gear 11, the cutting edge of said knife being essentially a portion of a logarithmic spiral. Said knife rotates on a horizontal axis with said gear, the blade being located between two plates, one of which, 17, is attached to the casting 18 by screws or other fastening means 19, and the other of which, 17^a, is a part of the casing.

The knife is located adjacent to the starting button 20, the latter serving when 15 pressed to bring the measuring rolls 21 and 22 into yielding engagement with the cloth 23 which the operator holds in a horizontal span between said rolls, said cloth being passed through an opening 24 in the casing 20 25 of said machine. Said rolls 21 and 22 are indicated in Figure 2 in idle position, separated sufficiently to permit the ready insertion of the cloth. The mechanism for lowering the upper roll against the lower roll 25 is not shown herein as it forms no part of the present invention. At the completion of the measuring operation, the operator depresses the notching button 18, thereby rotating the knife through nearly a complete 30 revolution in a clockwise direction, the limit of its rotation being indicated in dotted lines in Figure 1. It will be seen that the curve of the cutting edge is such that in any position of rotation, a tangent drawn to the 35 point where said curve intersects the upper surface of the guide plates 17 will be substantially vertical, the same inclining slightly in the direction of rotation and the angle of inclination remaining constant. The 40 goods therefore will be slit by the knife instead of being sheared, the knife operating easily and a clean cut resulting. The operation which rotates the knife serves also to separate the rollers, the mechanism therefor 45 not being shown herein as it forms no part of the present invention.

It will be evident that for a given angular movement of the lever 4 about its pivot, the knife 16 will be given a greatly increased 50 angular movement,—hence a slight movement of the lever will produce a complete revolution of the knife.

The invention is not to be limited to the structural features described herein except 55 where limitations appear in the appended claims.

I claim as my invention:

1. In a measuring machine, the combination of a measuring roller over which 60 the material to be measured may be drawn, a hand-actuated lever mounted to swing in a substantially vertical plane, a fixed plate, a rotary knife to co-operate therewith, mounted to rotate on a substantially horizontal axis adjacent to one end of the roll-

er, said knife consisting of a blade in a substantially vertical plane and having a cutting edge extending along a substantially spiral line adjacent to the path of movement of the edge of the material so that 70 when the knife is rotated on its axis, the cutting edge of the knife will move progressively along said plate and across the edge of the fabric, and means for rotating the knife from the lever with an increased 75 angular movement with respect to the angular movement of the lever.

2. In a measuring machine, the combination of a casing having an opening therethrough, a measuring roller mounted in the 80 casing adjacent the roller, and over which the material to be measured may be drawn, a hand-actuated lever pivotally mounted within the casing to swing in a substantially vertical plane downwardly toward said 85 opening, a rotary knife mounted to rotate in a substantially vertical plane and having a cutting edge located near said opening and disposed along a substantially spiral line, and means for rotating the knife 90 from the lever with an increased angular movement with respect to the angular movement of the lever.

3. In a device of the class described, the combination of a pivoted lever having a 95 segment, a pinion meshing with said segment, a knife blade mounted so as to turn with said pinion, said knife blade having a cutting edge in the form of a logarithmic spiral, and a guide plate adjacent said knife 100 blade.

4. In a device of the class described, the combination of a pivoted lever, a starting button at one end thereof with respect to the pivot point of the lever, a segment at the other end thereof, a pinion rotated by said segment, a knife blade rotated by said pinion, a guide plate having an edge arranged radially with reference to the axis of rotation of said blade, said blade having a 110 cutting edge and mounted so that the edge moves along said radial edge at substantially a right angle thereto.

5. In a device of the class described, the combination of a base plate, a support 115 thereon, a pair of measuring rollers, a lever pivoted to said support, a segment mounted toward one end of said lever, a button adjacent the other end of said lever, a pinion also carried by said support and meshing with said segment, a knife mounted in a plane substantially parallel to said rollers and turning with said pinion, a pair of guide plates between which said knife may rotate, said knife having a cutting edge of 125 variable radius, and a spring for holding said knife blade in normal position.

6. In a device of the class described, the combination of a pivoted lever having an extension constituting a segment, a pinion 130

meshing with said extension, a knife blade mounted so as to turn with said pinion, said blade having a cutting edge in the form substantially of a logarithmic spiral, and 5 a pair of guide plates between which said knife blade turns, said knife edge moving outwardly along the edges of said plates and being inclined slightly in the direction of travel to hold the goods against said guide plate edges. 10

In testimony whereof, I have subscribed my name.

DOUGLAS TURNER.
